UNITED STATES PATENT OFFICE.

MAX LEVI, OF BALTIMORE, MARYLAND, ASSIGNOR OF ONE-HALF TO ABRAHAM LEVI,
OF BALTIMORE, MARYLAND.

HEAD PROTECTOR FOR SLEEPING BERTHS.

Application filed January 25, 1923. Serial No. 614,791.

This invention relates to a head protector for berths of sleeping-cars or ships, and has for its object to provide a portable and detachable device which may readily be set up at one or both ends of a sleeping berth and held in such a position as to provide a yielding structure which, in case of a sudden shock that would cause a person lying in the berth to be thrown bodily forward, will 10 act as a yielding buffer and prevent serious injury to the occupant of the berth.

Another object of the invention is to provide a simple and compact device that may be detached and folded and readily tucked 15 away with bed-clothing and mattresses when used in the berths of sleeping-cars.

The invention is illustrated in the accompanying drawing, wherein,—

Fig. 1 shows a portion of a sleeping berth 20 in perspective with my improved device in place at one end thereof.

Fig. 2 illustrates a vertical cross-sectional detail through the protector,—the section being taken on the line 2—2 of Fig. 1.

Fig. 3 shows an enlarged sectional detail 25 through one of the frame bars of the protector together with a fragment of the yielding netting as the same would appear if cut on the line 3—3 of Fig. 1, and

Fig. 4 illustrates an enlarged sectional plan through the device as the same would appear if viewed on the line 4—4 of Fig. 1.

In illustrating the invention no attempt 35 has been made to accurately show any precise construction of mattress supporting-means because these features will vary according to the character of the berth,—that is, whether it be a sleeping-car berth or the berth in a stateroom of a ship.

In the present instance however the numeral 5, designates a mattress resting upon a suitable support 6, with the bed-coverings 7 and pillow 8 in place for a better understanding of the invention.

The partition wall which separates one compartment, section or stateroom from the next is indicated by the numeral 9.

The improved protector device is designed 50 to be set up at the end of the berth between the pillow 8 and the partition-wall 9 and is spaced from said wall for reasons that will presently be more clearly understood.

The protector, in this instance includes a 55 rectangular frame which is formed of two vertical end channel-bars 10 and upper and

lower horizontal angle bars 11 which connect the channel-bars.

The protector-frame is provided with means for detachably connecting it to the partition-wall 9, and in the present instance 60 this connecting means consists of an upper heavy wire bail 12, and a lower bail 13.

Each bail has an out-turned bend 14 at its end which extends through perforations in the end channel bars, as clearly shown in 65 Fig. 4 of the drawing, whereby to pivotally connect the bails to said vertical channel-bars and permit them to be swung vertically so as to be folded back against the inner side 70 of the frame.

In addition to the wire bails 12 and 13, the protector-frame also, has, in the present instance, a brace rod 15, extending downwardly from the upper end of each channel bar and the lower end of each of these 75 brace-rods is provided with a fork 16 for a purpose that will presently be explained.

The bails 12 and 13 and the brace-rods 15 are all attached to the rear side or face 80 of the protector-frame.

From the front side of each channel bar 10 and the vertical faces of the angle-bars 11, I punch a series of tangs 17 which are clearly shown in Figs. 3 and 4 of the drawings. These tangs are provided all the 85 way around the rectangular frame and their purpose is to serve as hooks over which a netting 18 may be caught whereby such netting may be stretched and held in a taut condition and from a yielding buffer. 90

It is immaterial to the present invention as to the character of the netting 18 but the same may be formed of fibre threads and readily detached for renovating.

To detachably connect the protector-frame 95 to the partition wall 9, I provide the latter, in the present instance, with a plurality of hooks 19 and 20 over which the wire-bails 12 and 13 may be hooked as clearly shown in Fig. 1 and to then steady the frame the 100 forked ends 16 of the brace-rods extend down over the hooks 20.

When the protector has thus been hung in place against the partition wall 9, the netting 18, will have position directly at 105 the rear of the pillow 8,—the netting thus being sustained in a vertical position spaced from the partition wall so that the netting may yield inwardly without striking or coming in contact with the partition wall 9. 110

It is believed to be obvious that when a person is lying on the mattresses with the head on the pillow, any shock causing the occupant to be thrown in a lengthwise direction head-first, will cause the head of the person to strike against the yielding netting which latter will act as a buffer and prevent the occupant's head from striking the hard partition wall and thus avoid serious injury.

The protectors may obviously be detached with facility; the wire-bails folded against the frame and the entire device may then be readily stowed away until again needed.

Having described my invention, I claim,—

In a head protector for sleeping berths the combination with a division partition between adjacent berths, of horizontal supporting means to sustain a mattress, a rectangular frame having a netting attached thereto, upper and lower wire bails having out-turned ends that are pivotally attached to the frame said bails being detachably connected to the partition and said frame and netting being held in an upright position with the lower horizontal edge of the frame below the upper surface of a mattress on the horizontal supports.

In testimony whereof I affix my signature.

MAX LEVI.
